UNITED STATES PATENT OFFICE.

HARRY CHAPMAN, OF SHEFFIELD, ENGLAND.

MEANS FOR OBSERVING THE WORKING CONDITIONS IN THE CYLINDER OF AN INTERNAL-COMBUSTION ENGINE.

Application filed July 25, 1922. Serial No. 577,476.

To all whom it may concern:

Be it known that I, HARRY CHAPMAN, a subject of the King of England, residing at Sheffield, in Yorkshire, England, have invented certain new and useful Improvements Relating to Means for Observing the Working Conditions in the Cylinder of an Internal-Combustion Engine (for which I filed an application for patent in Great Britain on the 10th August, 1921); and I do hereby declare that the following is a full, clear, and exact description of the same.

This invention relates to means for observing the working conditions in the cylinder of an internal combustion engine of the kind described in the specification accompanying my application for Letters Patent No. 475,790 filed 7th June, 1921, in which an opening to the combustion chamber of the cylinder is closed by transparent or translucent material and light from the combustion of fuel therein is reflected to the eye of an observer, means for preventing risk of injury in case of fracture of such transparent material being provided if desired. The object of the present invention is to provide improvements in such a device with a view to prolonging its life, simplifying its construction and increasing its utility.

According to the present invention a tap, cock or the like is provided for cutting off and protecting the transparent or translucent material from the combustion chamber. The light from the combustion chamber is transmitted and reflected by means of a prismatic body which may also be employed to close the opening to the combustion chamber. In a convenient construction a nipple or the like having a passage through it is fitted to the engine with one end of such passage in communication with the combustion chamber, the other end of the passage is closed by a prismatic body and a tap or cock is situated across the passage so as to be capable of opening or closing communication between the prismatic body and the combustion chamber, a displaceable shield having a viewing aperture being fitted over the prismatic body. A branch from the nipple passage to the atmosphere may be provided to relieve compression in the cylinder and to form a priming opening, both the branch and the main passage being controlled by the same tap or cock. A second branch to the atmosphere likewise con-

trolled by the same tap or cock may be fitted with a non-return exit valve, and be used for scavenging purposes.

The device may be combined with a sparking plug adapter having a chamber capable of receiving the plug electrodes and providing communication between the nipple passage and the engine combustion chamber. Such an adapter enables the device to be used for viewing the spark. If desired means may be provided for cooling the device.

The prismatic body employed to reflect rays from the engine combustion chamber may be in the form of a cylinder flanged at one end and bevelled or curved at the other, the flange being used for securing the body in position and the bevel or curve, which may be silvered, to reflect the light. When the prismatic body is curved it may be bevelled at the exterior bend and its free end may be rounded, to act as a magnifying glass. A flat face may, however, be formed on the prismatic body opposite the bevel, whether the cylinder is curved or not.

In the accompanying drawings:—

Figure 1 is an elevation partly in section of a device according to the present invention.

Figure 2 is a view similar to Figure 1 showing a modification.

Figure 3 is a sectional elevation and Figures 4 and 5 are elevations of parts of the device showing modifications.

Figures 6 and 7 are elevations showing further modifications and Figure 8 is a sectional elevation showing a modification of one of the parts.

Like reference numerals indicate like parts throughout the drawings.

In the construction illustrated in Figure 1 a nipple 1, which forms a tap body is provided with a passage 2 extending through it and controlled by a tap 3. The nipple 1 is screwed at one end as shown at 4 to enable it to be attached to the engine with one end of the passage 2 in communication with the combustion chamber. Conveniently the nipple may be screwed into one of the valve cap orifices or a special tapped hole may be provided in any suitable portion of the combustion wall or even in the exhaust pipe. The other end of the passage 2 is closed by a lens 5, the lens being conveniently mounted with asbestos

110

or other suitable packing in an internally flanged hollow extension 6 of a nut 7 by means of a ring 8. By screwing the nut 7 to the end of the nipple 1 the lens 5 may thus be caused to close the passage 2. A displaceable shield 9 is mounted on the exterior of the extension 6, being held thereon by friction which may be ensured by any suitable form of spring such as by slotting the open end of the shield, the exterior of the extension 6 being slightly conical if desired. A viewing aperture 10 is made in the shield 9 and a reflector 11 is carried in the shield opposite the viewing aperture 10.

When this device is in position the working conditions of the cylinder to which it is attached may be observed at will through the aperture 10 by opening the tap 3, the colour of the explosion flame forming a reliable indication of such conditions. At other times the lens 5 may be cut off and protected from the cylinder gases, oil, combustion products, and fuel, by closing the tap 3.

A branch 12 from the nipple passage 2 to the atmosphere may be provided in such a position and the tap spindle orifice 13 be of such size that both the passage 2 and the branch 12 may be controlled by the one tap 3. Thus by partially turning the tap handle upwards from the position shown in Figure 1, the branch 12 will be opened to the cylinder and will act as a compression relief, and by turning the tap handle still further the branch 12 will be closed and the lens 5 be placed in communication with the combustion chamber.

In the modification illustrated in Figure 40 the lens 5 and the reflector 11 are replaced by a single prismatic body 14 of glass or other transparent or translucent material. The prismatic body 14 which is shown detached in Figure 4 is constituted by a glass cylinder flanged at one end as shown at 15 and bevelled at the other end as shown at 16. The face of the cylinder opposite to the bevel 16 may either be left rounded or may be flat as indicated at 17. The flange 15 enables the prismatic body to be mounted in a gas tight manner in the extension 6, and if desired this end of the body 14 may be convex in shape to act as a lens.

Figure 5 illustrates a modified form of the prismatic body 14 in which the flanged cylinder is curved to reflect at the desired angle light passing through it. The mere curvature is sufficient in some cases although the exterior bend of the curve may be bevelled as shown in dotted lines in Figure 5 at 16 to provide a flat surface and to increase the brightness of the reflection. In all cases the curve or bevel may be silvered for a like purpose, although the silvering

is preferably omitted when the device is intended to be in continuous operation for long periods. The free end through which the light from the combustion chamber is viewed may either be flat or rounded as shown at 17^A to act as a magnifying glass.

In Figure 2 also a second branch 18 from the passage 2 to the atmosphere is illustrated, and this branch 18 is closed by a non-return exit valve 19. The branches 12 and 18 as well as the passage 2 are all controlled by the one tap 3. When this tap is placed in such a position as to open both the branch 18 and the part of the passage 2 above it to the cylinder these parts may be scavenged, the non-return exit valve 19 allowing waste gases to pass into the air, and preventing air from being drawn in. By opening both the branch 12 and the passage 2 simultaneously to the combustion chamber a similar result will be attained, but air will be admitted to the inner surface of the prismatic body 14.

In the modification shown in Figure 3 the prismatic body 14 is mounted in the displaceable shield 9, the passage 2 being closed by the lens 5 as in the form illustrated in Figure 1.

In some cases, especially when the engine is not provided with valve caps and in cases where it is inconvenient to provide additional openings into the combustion chamber, a device according to the present invention may be combined with a sparking plug adapter as shown in Figure 6, the one opening in the combustion chamber serving both for ignition of the fuel and to view the result. The adapter 20 is formed with a chamber 21 to receive the sparking plug electrodes the plug being screwed therein instead of in the combustion chamber. The adapter 20 is provided with a screwed or tapped boss 22 on to which the nipple 1 of the viewing device is screwed, the boss 22 having a passage through it entering the chamber 21 and forming a continuation of the passage 2 when the device is in position. The adapter is also provided with a threaded boss 23 to enable it to be fitted to the combustion chamber and this boss likewise is provided with a passage through it from the chamber 21. The combination of such an adapter with the viewing device enables the spark itself to be seen as well as the explosion flame.

Means for cooling a device according to the present invention may be provided if desired, Figure 7 illustrating cooling fins 24 on the nipple 1 and Figure 8 showing cooling fins 24 on an adapter 20 of slightly different shape from that shown in Figure 6. When the cooling fins 24 are situated between the tap 3 and the viewing device as shown in Figure 7 an additional scaveng-

ing aperture closed by a screw 25 may be provided if desired.

The displaceable shield 9 not only serves to cut off exterior light from the lens or the like closing the passage 2 but if such lens should happen to be fractured the shield will be blown off along the axial line of the extension 6 and nut 7 and will thus protect the observer from risk of injury.

10 By the employment of the present invention the viewing device may be permanently fitted to the engine if desired, the tap 3 protecting the lens, prismatic body or the like from the action of the explosive gases, 15 and flames when not in actual use. To clean the lens or its equivalent it is only necessary to unscrew the nut 7 whereby the inner face of the lens will be rendered accessible.

What I claim is:—

20 1. In an internal combustion engine, the combination with a nipple or the like having a passage through it, means for placing one end of the passage in communication with the combustion chamber of the engine, a prismatic body permitting the passage of light closing the other end of the passage, a cock capable of opening and closing communication between the prismatic body and the combustion chamber and 25 a displaceable shield over the prismatic body having a viewing aperture, substantially as specified.

2. In an internal combustion engine, the combination with a nipple or the like having a passage through it, means for placing one end of the passage in communication with the combustion chamber of the engine, a prismatic body permitting the passage of light closing the other end of the passage, a 30 cock capable of opening and closing communication between the prismatic body and the combustion chamber, a displaceable shield over the prismatic body having a viewing aperture, and a branch from 35 the nipple passage to the atmosphere, both the branch and the main passage being controlled by the same cock, substantially as specified.

3. In an internal combustion engine, the combination with a nipple or the like having a passage through it, means for placing one end of the passage in communication with the combustion chamber of the engine, a prismatic body permitting the passage of light closing the other end of the passage, a 40 cock capable of opening and closing communication between the prismatic body and the combustion chamber, a displaceable shield over the prismatic body having a viewing aperture, and two branches from 45 the nipple passage to the atmosphere, both branches and the main passage being controlled by the same cock, and one of the 50 branches being fitted with a non-return exit 55 valve, substantially as specified.

4. In an internal combustion engine, the combination with a passage opening to the combustion chamber, of a prismatic body closing the passage and transmitting and reflecting light from the combustion chamber, the prismatic body being in the form of a cylinder flanged at one end and having a surface at the other end reflecting light, transmitted axially through it, at an angle to its axis, substantially as specified. 70

5. In an internal combustion engine, the combination with a passage opening to the combustion chamber, of a prismatic body closing the passage and transmitting and reflecting light from the combustion chamber, the prismatic body being in the form of a cylinder flanged at one end and having a silvered surface at the other end reflecting light, transmitted axially through it, at an angle to its axis, substantially as specified. 75

6. In an internal combustion engine, the combination with a passage opening to the combustion chamber, of a prismatic body closing the passage and transmitting and reflecting light from the combustion chamber, the prismatic body being in the form of a cylinder flanged at one end and bevelled at the other substantially as specified. 90

7. In an internal combustion engine, the combination with a passage opening to the combustion chamber, of a prismatic body closing the passage and transmitting and reflecting light from the combustion chamber, the prismatic body being in the form of a cylinder flanged at one end and bevelled 95 and silvered at the other, substantially as specified. 100

8. In an internal combustion engine, the combination with a passage opening to the combustion chamber, of a prismatic body closing the passage and transmitting and reflecting light from the combustion chamber, the prismatic body being in the form of a cylinder flanged at one end, bevelled at the other and formed with a flat face opposite the bevel, substantially as specified. 105

9. In an internal combustion engine the combination of a nipple or the like having a passage through it, means for placing one end of the passage in communication with the combustion chamber of the engine, a prismatic body permitting the passage of light closing the other end of the passage in the form of a cylinder flanged at one end bevelled at the other and formed 110 with a flat face opposite the bevel, a cock capable of opening and closing communication between the prismatic body and the combustion chamber and a displaceable shield over the prismatic body having a viewing aperture, substantially as specified. 120

In testimony whereof I hereunto affix my signature.

HARRY CHAPMAN.
